UNITED STATES PATENT OFFICE.

CARL SCHRAMM, OF WEST HARTFORD, AND PAUL F. VOKAL, OF HARTFORD, CONNECTICUT, ASSIGNORS TO PRATT & WHITNEY COMPANY, OF NEW YORK, N. Y., A CORPORATION OF NEW JERSEY.

DRIVING CONNECTION.

Application filed June 4, 1924. Serial No. 717,794.

Our invention relates to driving connections and particularly to driving connections for operating thread grinding machines.

One object of our invention is to provide 5 a driving connection for a work carrying spindle and a lead screw that shall compensate for the back lash between the work spindle and the lead screw.

Another object of our invention is to provide 10 a driving connection for a thread grinding machine that shall be provided with a loose connection so constructed as to compensate for back lash and insure correct relative position between the grinding wheel 15 and the work when the work and the grinding wheel are axially moved relatively to each other in either direction.

In many machines, it is essential to maintain 20 the cutting tool and the work in correct relative position. Thus in grinding a thread, it is essential to maintain the rotating work or thread in a correct relative position with respect to the grinding wheel. In moving the work longitudinally past the 25 grinding wheel, it is not difficult to maintain the grinding wheel in correct position with respect to the threads being ground when the work is being moved in one direction past the grinding wheel. However, upon 30 reversing the longitudinal movement of the work, the back lash in the driving connection between the work spindle and the lead screw changes the relative position of the rotating work and the grinding wheel so as 35 to require a resetting of the work and the wheel with respect to each other.

In a machine constructed in accordance 40 with our invention, a loose connection is provided between either the work carrying spindle or the lead screw to compensate for the back lash in the driving connection serving to operate the machine. Preferably the loose connection is provided between the work carrying spindle and the driving connection. In practicing our invention, the 45 loose connection serves to prevent rotation of the work carrying spindle upon reversal in the direction of rotation of the spindle and the lead screw until the lead screw has 50 been rotated sufficient to take up all back lash in the driving connection. In the construction above set forth, it will be noted no means is used to prevent back lash but means is provided for compensating for the

back lash which necessarily more or less exists in all connections.

In the accompanying drawings:

Figure 1 is a front elevational view of a machine constructed in accordance with our invention.

Fig. 2 is an end elevational view of the machine shown in Fig. 1.

Fig. 3 is a detail view illustrating the wheel dressing slide.

Fig. 4 is a detail view of the means for controlling the wheel feeding movements.

Fig. 17 is a sectional view through the reversing mechanism.

Fig. 18 is a detail view of parts of the reversing mechanism in horizontal section.

Referring to the drawings, a thread or tap grinding machine is shown comprising a main frame 1 upon which is mounted a work carrying carriage 2 and a wheel slide 3. The carriage 2 is mounted upon suitable guides 4 and 5, and the slide 3 is mounted

upon suitable guides 6 and 7. The carriage 2 carries a headstock 8, which is preferably fixed to the carriage 2, and a tailstock 9 which is adjustable along the carriage 2 on 5 suitable guideways.

An auxiliary wheel slide 10 is supported on a suitable guideway in the slide 3, as best shown in Fig. 3 of the drawings. A nut 11, which projects from the bottom of 10 the auxiliary slide 10, engages a screw shaft 12. The screw shaft 12 serves to effect feeding movement of the wheel slide 3. The auxiliary slide 10 is connected to the wheel slide 3 by means of a nut 13 and a screw 15 shaft 14. The nut 13 is fixedly secured to the auxiliary slide 10 and engages the screw shaft 14 which is mounted on the wheel slide 3. Thus, it is apparent rotation of the screw shaft 12 serves to operate the wheel 20 slide 3 through the nut 11, auxiliary slide 10, the nut 13 and the screw shaft 14. The screw shaft 14 is operated, in a manner to be hereinafter set forth, when the grinding wheel is being dressed.

25 The wheel slide 3 is provided with a bracket 15 which serves to support a wheel supporting plate 16. The bracket 15 is provided with arcuate T-slots 17 which are engaged by bolts 18 for supporting the plate 30 16 in any set position. The plate 16 is provided with suitable bearings for the wheel spindle 19. The spindle 19 carries a grinding wheel 20 and a driving pulley 21. In the above construction, it will be noted the 35 plate 16 may be adjusted on the bracket 15 to angularly adjust the grinding wheel 20 with respect to the work being operated upon.

40 The pulley 21 is connected by a suitable belt 22 to a pulley 23 which is mounted on a power shaft 24. The belt 22 extends over two idler pulleys 25 which are mounted on the slide 3. A pulley 26, which is mounted on the main frame 1, is resiliently held in engagement with the belt 22 to take up any slack during the movement of the wheel slide with respect to the main frame.

45 A dressing slide 27 is provided for carrying a suitable dressing attachment to true the grinding wheel 20. The slide 27 is movable along a second slide 28 and may be locked to the second slide by means of a lever 29. The movement of the slide 28 is controlled by a hand wheel 29. The hand 50 wheel 29 not only serves to effect movement of the slides 28 and 27 for dressing the wheel but also serves to effect movement of the wheel slide 3 by means of the screw shaft 14. The hand wheel 29 is connected to a 55 short shaft 30 having a bevel gear wheel 31 mounted thereon. The bevel gear wheel 31 meshes with a bevel gear wheel 32 which is mounted on a shaft 33. The shaft 33 carries a spur gear wheel 34 and is provided 60 with screw threads 35 which engage a nut

36. The nut 36 is secured to the slide 28, as indicated on Fig. 2 of the drawings. The gear wheel 34 is connected to a gear wheel 38 which is mounted on and secured to the screw shaft 14. The gearing between the 70 shaft 38 and the shaft 14 is such as to effect a two to one movement between the slide 28 and the wheel slide 3. Thus, the dressing slide is moved twice as far as the wheel slide. Accordingly the grinding wheel 20 is always 75 maintained in adjusted position with respect to the work being operated no matter how much material is removed during the dressing operation.

80 The power shaft 24 carries a fast pulley 40 and a loose pulley 41, which are adapted to be connected by a belt 42 to any suitable source of power. A belt shifter of any suitable type is operated by a lever 43 for controlling the position of the belt 42 on the 85 pulleys 40 and 41. A spiral gear wheel 44, which is mounted on the power shaft 24 near the end thereof, meshes with a spiral gear wheel 45 which is mounted on a shaft 46. The shaft 46 is connected to a gear wheel 47 90 by means of a suitable clutch 48. The clutch 48 is controlled by a handle 49 which is mounted on a lever 50. The lever 50 is pivoted at 51 and operates a lever 52 by means of an arm 53. The lever 52 is pivotally supported at 54 on the main frame 1 and engages a bell crank lever 55. The bell crank lever 55 is provided with a bifurcated end portion which engages a collar formed on the clutch 48.

95 The gear wheel 47 meshes with a gear wheel 58 which is mounted on a shaft 59. The shaft 59 is located directly above the gear wheel 47. The shaft 59 also carries two gear wheels 60 and 61 and a clutch mechanism 62. The gear wheels 58 and 60 are loosely mounted on the shaft 59 and are adapted to be connected to the shaft according to the position of the clutch mechanism 62. The gear wheel 61, which is fixedly connected to the shaft 59, meshes with a gear wheel 63 which is fixedly mounted on a shaft 64. The shaft 64 carries a second gear wheel 65 which meshes with a gear wheel 66 on a short shaft 67. The shaft 67 carries 105 a pulley 68 for supplying power to rotate the work carrying spindle and to effect movement of the work carrying carriage 2.

110 The gear wheel 47 not only meshes with the gear wheel 58 but also meshes with a gear wheel 69 which is fixedly mounted on a shaft 70. The shaft 70 also carries a gear wheel 71 which meshes with the gear wheel 60 on the shaft 59. The gear wheel 71 is fixedly connected to the shaft 70 and is connected to a ratchet wheel 72. Between the ratchet wheel 72 and the gear wheel 69, a cam drum 73 is loosely mounted on the shaft 70. The cam drum 73 has a pawl disk 74 secured to it adjacent to the ratchet wheel 115 120 125 130

72. The disk 74 carries a pawl member 75 which is adapted to engage the teeth on the ratchet wheel 72. A spring member 76 is provided for exerting a force at all times 5 tending to move the pawl 75 into engagement with the teeth on the ratchet wheel 72. Two levers 77 and 78 which are located on opposite sides of the shaft 70 are provided for engaging the pawl 75 to move it out of 10 engagement with the ratchet wheel. The levers 77 and 78 are respectively mounted on short shafts 79 and 80 which also carry levers 81 and 82. The levers 81 and 82 are joined by a spring member 83 which exerts a 15 force tending to move the levers 77 and 78 in the path of movement of the pawl 75. One arm 84 of a bell crank lever 85 is disposed between the levers 81 and 82 and serves to operate the levers 81 and 82 in accordance with the movement of the carriage 2. The bell crank lever 85 is connected by a 20 reach rod 86 to a bell crank lever 87. The bell crank lever 87 is operated by two dogs 88 and 89 which are adjustably mounted on 25 the carriage 2. The dogs 88 and 89 serve to limit the extent of movement of the carriage 2.

Assuming the lever 77 to be in engagement with the pawl 75, as shown in Fig. 17 of the 30 drawings, and the pawl 75 to be held out of engagement with the ratchet wheel 72, the cam drum 73 is held stationary. However, upon engagement between the dog 89 and the bell crank lever 87, the arm 84 of the bell 35 crank 85 engages the lever 81 and moves the lever 77 out of engagement with the pawl 75. The pawl 75 engages the teeth of the ratchet wheel 72 and accordingly the disk 74 and the cam drum 73 are rotated with the 40 shaft 70. Such rotation of the disk 74 and the cam drum 73 continues until the pawl 75 is engaged by the lever 78. The lever 78 moves the pawl out of engagement with the ratchet wheel to prevent further movement 45 of the cam drum 73.

Upon engagement between the dog 88 and the bell crank lever 87 at the other end of the movement of the carriage 2, the lever 78 is moved out of engagement with the pawl 50 75 to effect a half rotation of the cam drum 73. This last movement of the cam drum is stopped by the lever 77 engaging the pawl 75 to disengage it from a ratchet wheel 72. The disk 74 is provided with two notches 92 55 which are fitted to a spring pressed plunger 93 to prevent any retrograde movement of the disk 74 and the cam drum 73.

The cam drum 73 has a cam groove 94 formed therein which operates a lever 95 to 60 control the clutch mechanism 62. The clutch mechanism 62, as heretofore set forth, serves to connect either the gear wheel 58 or the gear wheel 60 to the shaft 59. By such means it is apparent the pulley 68 is rotated 65 in a clockwise or in a counterclockwise direc-

tion to control the direction of rotation of the work carrying spindle and the direction of movement of the carriage 2.

The pulley 68 is connected by a belt 96 to a pulley 97. The pulley 97 is mounted on a 70 shaft 98 which is provided with suitable bearings on carriage 2. The belt 96 extends around an idler pulley 99 which is mounted on the main frame 1 of the machine and around two idler pulleys 100 which are 75 mounted on the carriage 2. The shaft 98 carries a spiral gear wheel 101 which meshes with a spiral gear wheel 102 on a shaft 103. The shaft 103 carries a gear wheel 104 which meshes with a gear wheel 105 on a shaft 106. 80 The shaft 106 is connected through a suitable lost motion connection 107 to the driving spindle 108. The shaft 103 also carries a pinion 109 which meshes with a gear wheel 110. The gear wheel 110 meshes with a gear 85 wheel 111. The gear wheel 111 is connected to a gear wheel 112 which meshes with gear wheel 113. The gear wheel 113 is fixedly connected to the lead screw 114 which effects movement of the carriage 2. 90

Referring to Figs. 1, 6 and 7 of the drawings, the lead screw 114 is connected to the carriage 2 by means of a nut 115 which has a worm wheel 116 secured thereto. The worm wheel 116, which is fixedly connected 95 to the nut 115, meshes with a worm 117. The worm 117 is formed on a shaft 118. The shaft 118 extends through the front of the machine and has a hand wheel 119 mounted thereon. The hand wheel 119 serves to effect adjustment of the carriage 2 with respect to the wheel 20 at will. 100

The lead screw 12, which operates the wheel slide 3, has a gear wheel 121 mounted on it, as shown in Figs. 1, 4 and 5 of the drawings. The gear wheel 121 meshes with a pinion 122 on a short shaft 123. The shaft 123 carries a gear wheel 124 which meshes with a pinion 125 on a shaft 126. The shaft 126 carries a hand wheel 127 for effecting feeding movement of the wheel slide 3 at will. The shaft 126 also carries a ratchet wheel 128 and a three armed lever 129. One arm 130 of the lever 129 carries a pawl 131. A second arm 132 of the lever carries a pawl 133 and a third arm 134 is connected by a link 135 to a bell crank lever 136. The bell crank lever 136 is operated by a plunger 137. The plunger 137 is operated by means of a dog 138 which is adjustably mounted on the work carrying carriage 2. The dog 138 operates the plunger 137 at each reciprocation of the carriage 2 and accordingly effects an oscillating movement of the three arm lever 129. If the pawl 131 is in engagement with the teeth of the ratchet wheel 128, an intermittent feeding movement of the wheel slide 3 will be effected. A shield 139, which is adjustable on the ratchet wheel, serves 110 to limit the total feeding to any desired 115 120 125 130

amount. The shield 139 extends over the teeth of the ratchet and prevents the pawl 131 from engaging the teeth when the wheel has been fed to a predetermined depth. The 5 arm 132 carries a handle 140 for feeding by hand when so desired. The amount of feed effected by the arm 132 may be controlled by means of a shield 141 which is supported on the main frame of the machine.

10 Referring to Figs. 1, 8, 9 and 10, one form of the loose connection is illustrated for compensating for the back lash in the gearing connected to the lead screw 114 and the work spindle 108. The shaft 106, which is connected to the work spindle 108 through the loose connection 107, projects through a sleeve 144 which is suitably secured to the headstock of the machine. Adjacent to the sleeve 144, an arm 145 is keyed to the shaft 20 106. The arm 145 carries a pin 146 which projects into position between two stop members 147 and 148. The two stop members are mounted on a cup-shaped member 149. The cup-shaped member 149 is keyed to the work 25 carrying spindle 108 as shown in Fig. 8 of the drawings. The pin 146 is adjustable in the arm 145 and is held in any set position by means of two set screws 150. A collar 151, which is threadably connected to the sleeve 144, engages a notch in the pin 146 and serves to adjust the position of the pin in the arm 145. A set screw 152 is provided for holding the collar 151 in any set 30 position on a sleeve 144. It may be noted 35 that the pin 146 may be adjusted by means of the collar 151 even if the shaft 106 and the spindle 108 are in rotation.

40 The pin 146 is provided with a tapered surface 153 which is adapted to engage the stop member 147 and a straight surface 154 which is adapted to engage the stop member 148. The stop member 147 is adjustable in a slot 155 and is provided with a tapered surface 156 which is adapted to engage the tapered surface 153 on the pin. The stop member 148 may be secured in any one of the holes 157 in the cup member 149 and is provided with a straight surface for engaging the straight surface 154 on the pin 146.

50 In the above construction, it will be noted, the work carrying spindle 108 is rotated by the pin 146 engaging one of the stop members 147 or 148. Inasmuch as the pin 146 does not simultaneously engage the two stop 55 members 147 and 148, it is apparent a reversal in the direction of rotation of the shaft 106 permits the driving connection to operate for a limited time before the work carrying spindle 108 is rotated. Thus, compensation is effected for the back lash between the lead screw 114 and the work spindle 108. The amount of loose connection between the shaft 106 and the work spindle 108 may be roughly adjusted by varying the 60 position of the two stop members 147 and

148. A fine adjustment of the loose connection may be effected by varying the position of the pin 146 in the arm 145.

Referring to Figs. 11, 12 and 13 of the drawings, a modification of our invention is 70 illustrated. The shaft 106 projects through a cup-shaped member 160 which is secured to the carriage 2. A hub member 161, which is suitably pinned to the shaft 106, is disposed adjacent the cup member 160 and 75 has teeth 162 formed on its periphery. A spider member 163 carries a number of pairs of pinions 164 and 165. Each pair of pinions 164 and 165 are rotatably mounted on a shaft 166 which is suitably secured to the spider member 163. Each of the pinions 165 meshes with the teeth 162 formed on the hub member and with teeth 167 which are formed on the cup member 160. Each of the pinions 164 meshes with teeth which are 80 formed on the inside periphery of a ring shaped worm wheel 168 and with teeth 169 which are formed on a hub member 170. The hub member 170 is rotatably mounted on the shaft 106 and carries a pin 171 which 85 projects through a slot 172 which is formed in a second cup-shaped member 173. The cup-shaped member 173 is fixedly connected to the shaft 106. The ring shaped worm wheel 168 is located between and supported 90 on the two cup members 160 and 173, as best shown in Fig. 11 of the drawings. The cup-shaped member 173 carries a pin 175 which is located at the same distance from the shaft 106 as the pin 171 is located. The two pins 171 and 175 are adapted to engage an arcuated lug 176 which projects from a disk 177. The disk 177 is fixedly connected to the work carrying spindle 108. A suitable worm shaft 178 is provided for effecting operation 100 of the worm wheel 168.

The pin 175 engages one end of the lug 176 to effect rotation of the spindle 108 in one direction and the pin 171 engages the other end of the lug 176 to effect rotation of the spindle in a reverse direction. The position of the pin 171 in the slot 172 may be adjusted to provide any amount of loose connection between the shaft 106 and the work carrying spindle 108. When the worm shaft 115 178 and the worm wheel 168 are held stationary, it is apparent the pin 171 rotates with the shaft 106. Such operation is apparent inasmuch as the cup member 160 and the worm wheel 168 are held stationary. The pinions 164 and 165 rotate at the same speed and consequently the hub member 170 is compelled to rotate at the same speed as the hub member 161. The rotation of the worm wheel 168 by the worm shaft 178 varies the position of the hub member 170 with respect to the hub member 161 and accordingly varies the position of the pin 171 in the slot 172. Referring again to Fig. 8 of the drawings, a suitable brake or friction device 130 179

What we claim is:

1. In a machine, the combination with a lead screw, a spindle, and a train of gears for rotating said spindle and the lead screw in a forward and in a reverse direction, of means for so connecting the spindle to the train of gearing as to insure a limited rotation of the lead screw prior to the rotation of the spindle upon change in the operation of the gearing to change the direction of rotation of the lead screw and the spindle. 70
2. In a machine, the combination with a lead screw, a work spindle, a carriage for the work spindle, a lead screw for operating said carriage, and means comprising a train of gears for rotating said spindle and the lead screw in a forward and in a reverse direction, of means for so connecting the spindle to said train of gears as to insure a limited rotation of the lead screw prior to the rotation of the spindle upon change in the operation of the train of gears to change the direction of rotation of the lead screw and the spindle. 80
3. In a machine, the combination with a lead screw, a carriage operated by said lead screw, a work spindle mounted on said carriage, and means comprising a train of gears for rotating the spindle and the lead screw in a forward and in a reverse direction, of a lost motion connection between the spindle and said train of gears to insure a limited rotation of the lead screw prior to the rotation of the spindle upon change in the operation of the train of gears to change the direction of rotation of the spindle and the lead screw, and means for varying the amount of said lost motion. 85
4. In a machine, the combination with a lead screw, a carriage operated by the lead screw, a work carrying spindle, and means comprising a train of gears for rotating the lead screw and the spindle in a forward and in a reverse direction, of a lost motion connection between said spindle and the gear train, and means for varying said lost motion connection to insure the rotation of the spindle and the lead screw in the same relation when rotating in a forward and in a reverse direction. 95
5. In a machine, the combination with a lead screw, a carriage operated by the lead screw, a work spindle mounted on said carriage, said spindle serving to carry a piece of work having a thread formed thereon, and means comprising a train of gears connected to the spindle and the lead screw for rotating them in timed relation, of a lost motion connection joined to the gear train, and means for adjusting said lost motion connection to compensate for the back lash in said gear train whereby the spindle and the lead screw may be rotated in a forward and in a reverse direction and maintain a correct relative position between them. 100
- Modifications in the mechanism and in the arrangement and location of parts may be made within the spirit and scope of our invention and such modifications are intended to be covered by the appended claims. 115

6. In a machine, the combination with two rotating members, and mechanism for rotating the two members in timed relation to each other and for rotating the members 5 in a forward and in a reverse direction, of a loose connection between one of the members and the said mechanism to compensate for the back lash in said mechanism upon reversal in the direction of rotation of the 10 members.
7. In a machine, the combination with a work carrying spindle and a lead screw for moving the work along a cutting tool, of a gear train for rotating the spindle and the 15 screw in a forward and in a reverse direction, and a lost motion connection between one of said members and the gear train to compensate for the back lash in the gear train.
8. In a machine, the combination with a work carrying spindle and a lead screw for moving the work along a cutting tool, of a gear train for rotating the spindle and the screw in a forward and in a reverse direction, and a lost motion connection between the spindle and said train of gears to compensate for the back lash in the gear train.
9. In a machine, the combination with a work carrying spindle, a lead screw for effecting relative movement between the work and a cutting tool, and means comprising a train of gear wheels for rotating the work spindle and the lead screw in a forward and in a reverse direction, of a lost motion connection between said gear train and the spindle and lead screw to compensate for the back lash in the gear train, said connection comprising a lug member located 30 between two stop members.
10. In a machine, the combination with a work carrying spindle, a lead screw for effecting relative movement between the work and a cutting tool, and means comprising a train of gear wheels for rotating the work spindle and the lead screw in a forward and in a reverse direction, of a lost motion connection between said gear train and the spindle to compensate for the back lash in the gear train, said connection comprising a lug member located between two stop members, and means for varying the relative position of the two stop members to vary the lost motion in said connection.
11. In a machine, the combination with a work carrying spindle, a lead screw for effecting relative movement between the work and a cutting tool, and means comprising a train of gear wheels for rotating the work spindle and the lead screw in a forward and in a reverse direction, of a lost motion connection between said gear train and the spindle to compensate for the back lash in the gear train, said connection comprising a lug member located between two stop members,
- and means for varying the position of the lug and for varying the relative position of the two stop members to vary the lost motion in said connection.
12. In a machine, the combination with a work carrying spindle, a lead screw for moving the work along a cutting tool, and means comprising a train of gear wheels for rotating the work spindle and the lead screw in a forward and in a reverse direction, of a lost motion connection between the work spindle and the gear train to compensate for the back lash in the gear train, said connection comprising two stop members rotating with the gear train and a lug 70 rotating with said spindle and located between the two stop members, and means for varying the position of the lug along the spindle axis and for varying the relative position of the two stop members to vary the amount of lost motion in the connection.
13. In a machine, the combination with a work carrying spindle, a lead screw for effecting relative movement between the work and a cutting tool, and means comprising a train of gear wheels for rotating the spindle and the lead screw in a forward and in a reverse direction, of a lost motion connection between the work spindle and the gear train to compensate for the back lash in the gear train, said connection comprising a lug 80 rotating with the work spindle, two stop members rotating with said gear train and respectively located on opposite sides of the lug member, and means for varying the relative position of the two stop members and for varying the position of the lug along the spindle axis to vary the amount of lost motion in said connection.
14. In a machine, the combination with a work carrying spindle, a lead screw for effecting relative movement between the work and the cutting tool, and means comprising a train of gear wheels for rotating the work spindle and the lead screw in a forward and in a reverse direction, of a lost motion connection between the work spindle and the gear train, said connection comprising a lug rotating with the work spindle and projecting between two stop members which rotate with said train of gear wheels, one of said stop members having a surface inclined with respect to the spindle axis for engaging a similar surface on the lug and the other stop member having a surface parallel to the spindle axis for engaging a similar surface on the lug, and means for varying the position of the lug to vary the amount of lost motion in the said connection.
15. In a machine, the combination with a work carrying spindle, a lead screw for effecting relative movement between the work and a cutting tool, and means comprising a train of gear wheels for rotating the work spindle and the lead screw in a forward and in a reverse direction, of a lost motion connection between said gear train and the spindle to compensate for the back lash in the gear train, said connection comprising a lug 90

ward and in a reverse direction, of a lost motion connection between the work spindle and the gear train, said connection comprising a lug rotating with the work spindle 5 and projecting between two stop members which rotate with said train of gear wheels, one of said stop members having a surface inclined with respect to the spindle axis for engaging a similar surface on the lug and the 10 other stop member having a surface parallel to the spindle axis for engaging a similar surface on said lug, and means for varying the relative position of the two stop members and for varying the position of the lug to vary the amount of lost motion in said 15 connection.

In testimony whereof, we hereto affix our signatures.

CARL SCHRAMM.
